UNITED STATES PATENT OFFICE.

JOHN H. McCORMICK, OF BEXLEY, OHIO.

DRAFT-GEAR FOR RAILWAY-VEHICLES.

1,127,656.

Specification of Letters Patent.

Patented Feb. 9, 1915.

Application filed November 14, 1910. Serial No. 592,141.

To all whom it may concern:

Be it known that I, JOHN H. McCORMICK, a citizen of the United States, residing at Bexley, in the county of Franklin and State 5 of Ohio, have invented certain new and useful Improvements in Draft-Gears for Railway-Vehicles, of which the following is a specification.

This invention relates to draft gears for 10 railway vehicles, and is designed as an improvement of my friction draft and buffering apparatus, Patent No. 719,949, and the pending application for Letters Patent, filed by me June 8, 1908, Serial Number 437,307. 15 This improved construction contemplates the provision of a draft gear wherein additional strength and friction surface will be obtained without increasing the size or weight of the device, at the same time more 20 evenly distributing the pressure than it has been heretofore.

It also is designed to provide an outside spring which is readily accessible when the same becomes damaged, or is to be inspected.

25 A further object of this invention is to insure the positive return of the elements under the highest possible resistance, after compression and also to provide means whereby the compression friction or resistance may be increased without in any way changing the release resistance.

With the above and other objects in view, this invention consists in the construction, combination and arrangement of parts, all 35 as hereinafter more fully described, claimed and illustrated in the accompanying drawings, wherein:

Figure 1 is a central longitudinal horizontal section of a draft gear constructed in accordance with the present invention, Fig. 2 40 is a transverse section taken on line 2-2 of Fig. 1, certain details being omitted for a more ready appreciation of the essentials, Fig. 3 is a similar view taken on line 3-3 45 of Fig. 1, parts thereof being eliminated, Figs. 4, 5 and 6 are details of the pockets formed in the forward wedging device.

Referring more particularly to the drawings, 10 indicates the forward wedging device and 10' indicates the rear wedging device said wedging devices being tubular in cross section and having their outer ends closed. The forward wedging device 10 is provided with a collar 11 adjacent to its

outer end, while the rear wedging device 10' 55 is provided with a similar collar 11'. A series of pockets 12, 12^a and 12^b are formed in the wedging element 10 adjacent to the inner surface of the collar 11 and are arranged centrally at the terminals of the 60 radii of said wedging device, disposed relatively at angles of 120 degrees. The rear wall of the pockets 12, 12^a and 12^b are of increasing thickness, the wall of the pocket 12^b being of greater thickness than the wall 65 of the pocket 12. The front walls 13 of the pockets are of a uniform thickness and have their inner surfaces beveled at an acute angle of a small number of degrees. From this description, it will be readily understood that the pockets 12, 12^a and 12^b are of 70 equally decreasing size, dependent upon the gradually increasing thickness of the forward walls thereof. The rear tubular member or wedging device 10' is provided with 75 a series of pockets 14, said pockets being disposed adjacent to the inner side of the collar 11' and arranged similarly to the pockets of the forward wedging device. These pockets 14 are of uniform size and 80 have the forward faces thereof open for the purposes hereinafter more fully described. The inner wall 15 of the pockets 14 are sloped or beveled at an acute angle, of a greater number of degrees than the slope 85 or bevel of the acute angle of the inner wall 13 of the pockets 12, 12^a and 12^b. The provision of the collars 11 and 11' at or near the point of location of the pockets, is particularly advantageous in that a greatly increased rigidity of structure is effected 90 which necessarily gives a maximum facility for wear and strength.

A series of friction elements 16 are arranged in the tubular members or wedging 95 devices 10 and 10', said friction elements forming a cylindrical member when combined, the outer surface of which gradually slopes to a central peripheral point. Each alternate friction element 16 is oppositely 100 arranged, said friction elements having the lugs 17 formed at one terminal thereof. As there are six of these friction elements, there are consequently six lugs, three of which are located in the pockets 12, 12^a and 12^b of 105 the forward wedging device, and three of which are contained or housed within the pockets 14 of the rear wedging or tubular

member 10'. The slope of the outer faces of the lugs 17 conforms to the slope of the inner faces of the pockets in which said lugs are housed.

- 5 A coiled spring 18 encircles the inner terminals of the wedging devices and bears as a forward terminal against the pockets 12, 12^a and 12^b and at its inner terminal against the lugs 17 housed in the pockets 14. It is 10 essential in these devices that the elements be as few and as accessible as possible and the provision of the spring in external relation to all of the parts is particularly advantageous.
- 15 The entire device is mounted between the followers 19 which bear against the outer surfaces of the collars 11 and 11'. The bearing of the followers at this particular point is particularly advantageous, since 20 this is the point subject to the greatest strain and shock. It will be noted that the contacting surfaces of the followers 19 and the collars 11 and 11' are in the form of concentric arcs to give a slight universal movement and play to the parts. The draft gear constructed as heretofore described, is 25 mounted on a car in the usual and standard manner.

From this construction, it will readily be understood that after the compression of the friction elements of this invention, has taken place, the release thereof should be of a positive nature and yet eliminate all shocks and to have at the same time a gradual movement. To provide for this and at the same 35 time eliminate the great strain which naturally is exerted upon the spring, the pockets 12, 12^a and 12^b are constructed as heretofore described and it will be understood 40 that the spring acting upon said pockets, will force the tubular member outwardly. This movement causes the inner wall of the pockets 12, 12^a and 12^b to successively contact with the projections 17 housed 45 therein. Thus it will be seen that the friction elements 16 carrying these projections, will be started, not simultaneously, but at different intervals of time until the inner walls of the pockets all bear against their 50 corresponding projections; at which time said friction elements will move simultaneously.

It will be noted that the inclines of the walls 13 and the coacting inclines of the 55 lugs or shoulders 17 are greater than the inclines of the walls 15 and consequently the wedging action of the walls 13 with the shoulders 17, is much greater and more difficult of release. This is compensated for by 60 the provision of the spring 18 bearing against the member 10 at one end, but against the segmental sections 16 at its other end. Thus the segmental sections having their shoulders at one end, will be maintained substantially immovable and the

spring will force the element 10, against the shoulders embraced thereby, to a point to release the sections successively.

What I claim is—

1. In a draft gear, a friction structure 70 comprising a plurality of friction elements having external friction surfaces, a cap for each end of said friction elements forming complementary friction elements, and a spring encircling said elements and said caps and forcing said caps apart. 75
2. In a draft gear, a friction structure comprising a plurality of sectoral elements in frictional engagement with each other when in assembled relation and having external friction surfaces, a cap for each end of said friction elements forming complementary friction elements therewith, and a spring encircling said elements and said caps and forcing said caps apart. 80
3. In a draft gear, a friction structure comprising a plurality of elements in assembled relation and increasing in assembled diameter toward a central point, complementary friction caps for the ends of said assembled elements, and a spring encircling said elements and a portion of said caps and tending to force said caps apart. 90
4. In a draft gear, a friction structure comprising a plurality of sectoral elements 95 in assembled relation and increasing in assembled diameter toward a central point, internally flaring caps inclosing the ends of said assembled elements, and a spring normally forcing said caps apart and encircling 100 said elements and caps.
5. In a draft gear, a friction structure comprising a plurality of sectoral elements in assembled relation, friction caps on the ends of said elements, collars integrally 105 formed on said caps and having rounded outer surfaces, bearing members having surfaces bearing against the rounded surfaces of said collars, and a spring for normally forcing said collars apart. 110
6. In a draft gear, a friction structure comprising sectoral members in assembled relation, friction caps on the ends of said assembled elements and having internal pockets, shoulders on said elements loosely 115 fitting in said pockets, a spring for forcing said caps apart, the inner walls of the pockets being relatively stepped to have successive contact with said shoulders under the effect of said spring. 120
7. In a draft gear, a plurality of friction elements, complementary friction caps upon both ends of said elements, wedging surfaces on said caps, means for successively releasing certain of said friction elements, 125 wedging surfaces on the successively released elements, and comparatively abrupt wedging surfaces on the other of said elements.
8. In a draft gear, a plurality of friction 130

elements having friction faces and wedging faces, a complementary member at each end of the assembled friction elements, each member having wedging faces for coaction 5 with the wedging faces of said assembled elements, a spring for normally maintaining release position of said assembled elements and bearing directly against one end of the assembled elements and against the 10 complementary member engaging the opposite end of said assembled elements, the wedging faces on the end of said assembled elements on which said spring bears directly being more abrupt than the wedging face in 15 the opposite end of said assembled elements.

9. In a draft gear, a friction structure comprising a plurality of sectoral elements in assembled relation, shoulders on said elements disposed at opposite ends of adjacent 20 elements, caps frictionally mounted on the ends of said assembled elements and having pockets for the loose reception of said shoulders, a spring for forcing said caps apart, the inner walls of the pockets of one cap 25 being relatively stepped to successively move the elements whose shoulders they embrace.

10. In a draft gear, a friction structure

comprising a plurality of sectoral elements in assembled relation, shoulders on said elements having wedging inclines disposed at opposite ends of adjacent elements, caps frictionally mounted on the ends of said assembled elements and having pockets for the loose reception of said shoulders, the 30 wedging inclines of one set of shoulders and the pockets in their cap being greater than those in the other cap, and a spring bearing against one cap and against the shoulders 35 within the other cap.

11. In a draft gear, a plurality of sectoral friction elements in frictional engagement with each other when in assembled relation and having external friction faces, complementary friction caps for the ends of said assembled elements, a spring for normally maintaining said elements in release position, and socketed follower heads for supporting the assembled gear by engagement 40 with said caps.

In testimony whereof I affix my signature in presence of two witnesses.

JOHN H. McCORMICK.
